ELECTRIC DISCHARGE MODULATING
SYSTEMFred B. Stone, Haddon Heights, N. J., assignor to
Radio Corporation of America, a corporation of
Delaware

Application January 31, 1935, Serial No. 4,213

7 Claims. (Cl. 250—20)

The present invention relates to electric discharge modulating systems and more particularly to a system of that character wherein modulation or signal mixing is effected in a single electric discharge device or tube. A specific system of the character referred to, and to which the invention is particularly adapted, is known commercially as a combined detector-oscillator wherein a single electric discharge device or tube 5 functions in connection with an oscillator circuit and a first detector circuit, as a signal mixing device.

An electric discharge device adapted for use in a combined detector-oscillator circuit may be of the pentagrid converter type such as an RCA A7 tube, having a cathode, an output anode, a signal input or control grid more adjacent to the anode, an oscillator grid and an oscillator anode electrode more adjacent to the cathode than the signal grid, and a screen grid for the signal grid.

Although screening is employed and suitable shielding of the external circuits, it has been found that the signal grid may have an appreciable mutual conductance to the oscillator anode, resulting in a degree of undesired energy transfer between the detector and oscillator portions of the system depending upon the frequency to which the oscillator is tuned with respect to the signal frequency. The energy transfer by regeneration or degeneration may be sufficient to appreciably impair the operation at ultra high frequencies such as are used in certain signal bands with all-wave receivers.

Accordingly, it is an object of the present invention to provide an improved modulating or signal mixing system embodying a single electric discharge device, wherein degeneration or regeneration in the signal input circuit is prevented more effectively, and whereby such system may be operated at ultra high frequencies with improved efficiency.

It is a further object of the present invention to provide an improved electric discharge device for signal mixing circuits and the like having two anode electrodes, one being more adjacent to the cathode than the other, and a signal input or control electrode between said anode electrodes, wherein the effect of mutual conductance between the signal input or control electrodes and one of the anode electrodes is materially reduced.

The invention will, however, be understood from the following description when considered in connection with the accompanying drawing, and its scope will be pointed out in the appended 55 claims.

In the drawing, Figure 1 is a schematic circuit diagram of a modulation or signal mixing system embodying the invention, and

Fig. 2 is a schematic representation of a modification of an electric discharge device or tube 5 adapted for use in the circuit of Fig. 1, in accordance with the invention.

Referring to Fig. 1, 5 is an electric discharge device having a cathode 7, an output anode electrode 9 and a control or signal input grid 11. The device is further provided with an additional grid electrode 13 and a second electrode 15 serving as an anode electrode, both being located between the cathode and the control grid. The device is also provided with a screen grid 17—17 serving 15 to shield the control grid 11 from both the anode 9 and the electrodes 13 and 15.

In connection with this device is shown a usual "pentagrid converter" or combined detector-oscillator circuit, comprising a signal input circuit 21, a signal output circuit 23 and an oscillator circuit 25, the input circuit being connected with the control grid 11 through a lead 27, and the oscillator circuit being connected with the electrodes 13 and 15 and including a feed-back winding 29 in circuit with the electrode 15 and coupled with the circuit 25 for utilizing said electrodes as an oscillator. The oscillator anode 15, the screen grid 17 and output anode 9 receive suitable operating potentials from tap points 31 on a suitable 30 potential source such as a resistor 33 which is supplied with rectified or direct current through leads —B and +B.

Biassing potential for the oscillator grid 13 is provided by the usual coupling condenser 35 and 35 grid leak 37, while biassing potential for the control grid 11 is provided through the input circuit 21 and an automatic volume control circuit connection 39 in series therewith, and a self-bias resistor 41 in the cathode lead 43.

In a radio receiving system of which the circuit shown may form a part, high frequency signals are supplied through the circuit 21 from a suitable source such as a high frequency circuit 45, and are mixed in the electronic stream of the device 5 with oscillations provided by the circuit 25—29 and the electrodes 13 and 15, to provide an intermediate frequency in the output circuit 23. An intermediate frequency output circuit, coupled with the circuit 23, is indicated at 47, and 50 may lead to a suitable intermediate frequency amplifier (not shown). As this type of combined detector-oscillator is at present well known and understood, further description is believed to be unnecessary.

The circuit thus far described may, however, be taken as representing any modulating or signal mixing circuit or system embodying a single electric discharge device having a plurality of electrodes including a signal input electrode and two anode electrodes, one of which is more adjacent to the cathode and with which the control electrode or signal grid has a negative mutual conductance.

It has been found that when the circuits 21, 25, and 29 are operated at relatively high frequencies such as are now generally employed in all-wave receivers, for example, there is a degenerative effect upon the circuit 21 connected to the detector or input grid 11. This has been found to be caused in part by the mutual conductance of the control grid 11 on the current to the electrode 15 which operates as the oscillator anode. This mutual conductance is negative in the usual sense. That is, making the grid 11 more negative causes the current to the anode electrode 15 to increase. At the same time its mutual conductance to the main anode 9 is normal, or positive, the anode current through the electrode 9 being decreased in value when the grid 11 is made more negative.

The increase of current to the anode 15 causes an increased potential drop across the inductance 29 and the resulting potential is applied, through the tube capacity between the electrode 15 and the electrode 11, to the input circuit 21 substantially 180° out of phase with the incoming signal.

In a combined detector-oscillator or mixer tube which is satisfactory in operation, the interelectrode capacity between the control grid and the oscillator anode electrode, in spite of suitable shielding or screening, is effective at the higher frequencies to permit feed-back coupling of the type described.

The feed-back is degenerative with respect to the signal applied to the control grid when the oscillator circuit is operated at a higher frequency than the incoming signal, which is the usual condition. If the oscillator is operated at a lower frequency than the incoming signal, the feed-back is regenerative which may also be undesirable.

In order to prevent undesired degeneration and regeneration effects in the input circuit of a combined detector-oscillator or mixing tube, the tube element geometry is so arranged that while the device may function as a mixer or converter effectively, the mutual conductance of the control grid 11 to the electrode 15 and to an electrode 51 are numerically as nearly equal as possible. It has been found that the electrode 51 may be inserted in the electronic stream of the device 5 more adjacent to the main anode electrode, whereby the control grid 11 may have a mutual conductance thereto equal and opposite to its mutual conductance to the oscillator anode electrode 15. The capacitances between the control grid 11 and the electrodes 15 and 51 are also, preferably, as nearly equal as possible.

With this arrangement, the mutual conductance from the grid 11 to the electrode 51, being positive, operates in a direction to cancel the effect of the negative mutual conductance to the electrode 15, when the two electrodes 15 and 51 are connected in circuit with each other as indicated at 53.

In practice the electrodes 15 and 51 are preferably of similar construction and may be in the form of grids, rods or plates located in the electronic stream of the device on opposite sides of

the control grid 11. In the present example, they are shown as being grid-like in structure.

In Fig. 2, to which attention is now directed, the device 5 is shown with the electrodes in the form of rods or plates 55 and 56, the rods or plates 55 being located on one side of the control grid 11 while the rods or plates 56 are located on the opposite side of said control grid in the electronic stream of the device. Any suitable construction, however, may be employed which permits the passage of electrons from the cathode 7 through to the anode 9. The rods or plates 55 or 56 represent any suitable number of such elements interconnected to form electrodes having opposing mutual conductance with respect to the control grid 11.

While the invention has been described in connection with a mixing device or modulator of the "pentagrid" converter type, it should be understood that any suitable electric discharge device may be employed which is adapted for signal mixing in connection with a plurality of signal circuits, and which is further adapted for neutralizing the effect of mutual conductance of control or signal input grid, and an electrode to which it has a negative mutual conductance and in circuit with which there is sufficient impedance to cause feed-back coupling to the said signal input grid.

I claim as my invention:

1. In an electric signalling system, the combination of an electric discharge device having a signal input electrode, a signal output electrode and additional oscillator electrodes coupled to generate oscillations including an oscillator anode electrode to which said input electrode has a mutual conductance, and means for providing in connection with said oscillator anode electrode a second electrode to which said signal input electrode has substantially an equal mutual conductance of opposite polarity.

2. In an electric signal receiving system, the combination of a detector-oscillator comprising an electric discharge device having a cathode, an oscillator grid, an oscillator anode electrode, a signal grid and an output anode, and signal input and output circuits and an oscillator circuit connected therewith to provide signal mixing therein, and means including an additional electrode for preventing energy transfer through said device from the oscillator circuit to the signal input circuit, said electrode having a mutual conductance with the signal grid substantially equal and opposite in polarity to the mutual conductance of said signal grid with the oscillator anode electrode, and being connected with the oscillator anode electrode.

3. In an electric signal receiving system, the combination of a detector-oscillator comprising an electric discharge device having a cathode, an oscillator grid, an oscillator anode electrode, a signal grid and an output anode, and signal input and output circuits and an oscillator circuit connected therewith to provide signal mixing therein, and an electrode having a mutual conductance with the signal grid substantially equal and opposite in polarity to the mutual conductance of said signal grid with the oscillator anode electrode, and a connection between the oscillator anode electrode and said additional electrode, thereby to neutralize the last named mutual conductance.

4. A combined detector-oscillator comprising an electric discharge device having a cathode, an output anode and a plurality of electrodes inter-

posed therebetween along the electronic path and comprising a control grid adjacent to the cathode, a second control grid more adjacent to the anode, a screen grid for said last named electrode, 5 a second anode electrode more adjacent to the first named control grid and the cathode, an impedance device in circuit with said second anode electrode, means for supplying feed-back energy from said last named electrode to said first named 10 control grid, and means for neutralizing the mutual conductance between the second named control grid and said second anode electrode.

5. A combined detector-oscillator comprising an electric discharge device having a cathode, an 15 output anode and a plurality of electrodes interposed therebetween along the electronic path and comprising a control grid adjacent to the cathode, a second control grid more adjacent to the anode, a screen grid for said last named electrode, a 20 second anode electrode more adjacent to the first named control grid and the cathode, an impedance device in circuit with said second anode electrode, means for supplying feed-back energy from said last named electrode to said first named control grid, and means for neutralizing the mutual 25 conductance between the second named control grid and said second anode electrode, said last named means including an additional electrode

corresponding to said second anode electrode located more adjacent to the main anode electrode, and means providing a circuit connection between said additional electrode and the second anode electrode.

6. In an electric signal modulating system, the combination of an electric discharge device having a control grid and an oscillator anode electrode to which the control grid has a mutual conductance, and means providing a second electrode 10 to which the control grid has an equal mutual conductance of opposite polarity, said second electrode being connected with the first named oscillator electrode, thereby to neutralize the first named mutual conductance.

7. In an electric signal modulating system, the combination with signal input and output circuits, of an electric discharge device having a cathode, a signal output anode, a signal input grid and an oscillator anode electrode to which 20 the control grid has a mutual conductance, and means providing a second electrode to which the control grid has an equal mutual conductance of opposite polarity, said second electrode being connected in circuit with said oscillator anode 25 electrode, thereby to neutralize the said mutual conductance.
